CLAIM

The ornamental design for an accumulator for banknote sorting machine, as shown and described.

DESCRIPTION

FIG. 1 is a perspective view of an accumulator for banknote sorting machine, showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof;
FIG. 7 is a left side elevational view thereof; and,
FIG. 8 is another perspective view thereof, shown in a position of use with an additional environmental counter. The broken lines in FIG. 8 showing the additional counter depict environment only and form no part of the claimed
